UNITED STATES PATENT OFFICE.

GEORGE S. HILL AND AUGUSTUS C. SAXTON, OF CHICAGO, ILLINOIS, ASSIGNEES, BY
DIRECT AND MESNE ASSIGNMENTS, TO H-E MANUFACTURING COMPANY, OF
CHICAGO, ILLINOIS, A CORPORATION OF ILLINOIS.

LOCK.

Application filed February 18, 1921. Serial No. 445,946.

To all whom it may concern:

Be it known that we, GEORGE S. HILL and AUGUSTUS C. SAXTON, citizens of the United States, residing at Chicago, in the county of 5 Cook and State of Illinois, have invented new and useful Improvements in Locks, of which the following is a specification.

The present invention relates to locks and more particularly such as are designed for 10 use in connection with the steering column of an automobile. Among the objects of this invention are: to so simplify the construction of a lock of this character as to make it more easy to assemble; to so improve 15 the construction of such a lock that the same will be strengthened; to so construct a lock of the character stated that the parts cannot readily get out of place and therefore cease to function properly; to provide 20 means, inaccessible from the exterior of the lock, for holding the lock cylinder in place in the structure and such further objects, advantages and capabilities as will later more fully appear.

25 Our invention further resides in the combination, construction and arrangement of parts illustrated in the accompanying drawing, and while we have shown therein a preferred embodiment, we desire the same to be 30 understood as illustrative only and not as limiting our invention.

In the drawing annexed hereto and forming a part hereof, Fig. 1 is a sectional plan view of a lock constructed in accordance 35 with our invention; Fig. 2 is a broken sectional view substantially along the plane indicated by the line 2-2 Fig. 1; and Fig. 3 is a transverse section substantially along the plane indicated by the line 3-3 Fig. 1.

40 Referring more in detail to the drawing, numeral 1 indicates the casing in which are housed the lock parts, 2 the spring pressed locking plunger, held in extended position by the spring 3 engaging its outer end, and 45 4 the lock cylinder extending inwardly through a lateral face of the body 1 to engage a flange 5 formed at the rear end of the locking bolt 2 by cutting away a portion of the body thereof to form a notch 6 in 50 which the operating finger 7 of the cylinder cam 8 may work. The head 9 of the locking bolt 2 is cut away as at 10 to slide over the upper face of the latch member 11 as shown in Fig. 3. This latch member 11 is carried

adjacent the lower end of a bolt 12 which is 55 biased outwardly by a spring 13 surrounding the bolt, and enclosed between the inner face of the bolt head 14 and the bottom of a cavity in the body member 1. The lower end 15 of the bolt 12 is reduced and slides 60 in a hole in the body member 1 to assist in holding and guiding the bolt 12 in its motions of reciprocation. The latch 11 is provided with a notch 16 adapted to engage in the notch 10 in the edge of the flange 9 when 65 the bolt 2 is withdrawn from locking position and the spring 13 causes latch member 11 to be raised. It is obvious that when a key is inserted in the lock cylinder and rotated it will cause the withdrawing of the 70 locking bolt to such a point that latch 11 may be raised by spring 13 until flange 9 engages in notch 16. In this position of the parts the lock cylinder may be rotated to 75 normal position and the key withdrawn. When it is desired to lock the steering post so that the machine may not be steered it is only necessary to press down on bolt head 14 until plunger or bolt 2 is released and then rotate the steering wheel sufficiently 80 to permit the plunger 2 to enter an aperture provided therefor as shown at 17 Fig. 2.

It will be seen by reference to the drawing that the locking plunger 2 is cut away only at one side (to form notch 6) instead 85 of being cut away in two or more places as has been heretofore done. The depth of notch 6 can be varied within certain limits and still leave the locking bolt strong enough to withstand any strains which may be put 90 upon it when an attempt is made to destroy it.

An aperture is formed in the body member 1 extending from the steering column aperture to the lock cylinder aperture and 95 is tapped for a portion of its length to receive the screw 19, which is inserted from the steering column aperture to engage and hold the lock cylinder 4 in place. This screw 19 is not exposed at any point upon the external surface of the body member 1 and therefore cannot be reached by any tool from the exterior of the lock so as to be removed 100 to release the lock cylinder.

A flanged sleeve 20 provided in one side 105 with a slot 21 surrounds the locking bolt 2 and is fitted in the aperture in body member 1 through which the locking bolt slides.

The locking bolt 2 is provided with a pin 22 adapted to rest and slide in the slot 21 to serve as a stop for locking bolt 2 and to assist in preventing rotation of said bolt under the pressure exerted by latch 11 and spring 13. A flat face 23 on flange 5 may engage the inner face of cam 8 to also assist in preventing rotation of the locking bolt.

It is of course understood that the specific description of structure set forth above may be departed from without departing from the spirit of our invention as set forth in this specification and the appended claims.

Having now described our invention, we claim:

1. In a steering post lock, a body member apertured for the reception of a slidable locking bolt and a lock cylinder, a sleeve in one of the apertures through which a locking bolt may pass, a headed locking bolt slidable through said sleeve, means for actuating said bolt, the head of said locking bolt being notched for the reception of a latch member, and a notched latch member adapted to rest in said notch in the bolt head and to be forced upwardly when the bolt head is withdrawn into registry with the notch in the latch member, so that the latch will be in position to hold the locking bolt in retracted position, said locking bolt being provided with means to prevent rotation thereof within the sleeve.

2. In a steering post lock, a body member apertured longitudinally and transversely

for the reception of a locking bolt and a lock cylinder, a lock cylinder in one of said apertures to actuate the locking bolt, means insertable and removable only from the interior of the lock for holding the lock cylinder in position, a slotted sleeve in the longitudinal aperture of the body member, a locking bolt slidable through said sleeve, said bolt being notched on one side only, the notch in the locking bolt co-operating with a cam on the lock cylinder to permit the actuation of the locking bolt and a projection on the locking bolt extending into the slot in the sleeve to prevent rotation of the bolt relatively to the sleeve.

3. In a steering post lock, a body member apertured for the reception of a slidable locking bolt and a lock cylinder, a headed locking bolt slidable through one of the apertures, means for actuating said bolt, the head of said locking bolt being notched for the reception of a latch member, and a notched latch member adapted to rest in said notch in the bolt head and to be forced upwardly when the bolt head is withdrawn into registry with the notch in the latch member, so that the latch will be in position to hold the locking bolt in retracted position.

In witness whereof, we hereunto subscribe our names to this specification.

GEORGE S. HILL.
AUGUSTUS C. SAXTON.
